CLAIM

The ornamental design for a communication and sensor hub belt clip, as shown and described.

DESCRIPTION

FIG. 1 is a perspective view showing the new design for a communication and sensor hub belt clip. As shown, the communication and sensor hub belt clip is oriented vertically;

FIG. 2 is a front view thereof;

FIG. 3 is a rear view thereof;

FIG. 4 is a side view thereof;

FIG. 5 is a top view thereof;

FIG. 6 is a bottom view thereof; and,

FIG. 7 is a perspective view thereof with a communication and sensor hub positioned within the belt clip.

The broken lines depict environment and are included for the purpose of illustrating only and form no part of the claimed design.
